(57) **CLAIM**

We claim the ornamental design for a telephone, as shown and described.

DESCRIPTION

FIG. 1 is a front perspective view of a telephone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front view thereof, in which a module in broken line is provided to illustrate environmental subject matter;

FIG. 9 is another front view of FIG. 8, in which a portable terminal in broken line is provided within the broken line module to illustrate environmental subject matter;

FIG. 10 is another right-side view thereof, in which the telephone is provided in an alternate position;

FIG. 11 is another right-side view thereof, in which the telephone is provided in an alternate position; and,

FIG. 12 is another right-side view thereof, in which the telephone is provided in an alternate position.

The broken lines in the figures show portions of the telephone which form no part of the claimed design.

The broken line showing of the module and portable terminal in FIGS. 8 and 9 is for environmental purposes only and forms no part of the claimed design.

1 Claim, 10 Drawing Sheets
